ALLERGEN APPLICATOR AND SKIN TESTER

Charles O. Morse, Redwood City, Calif.

Application December 4, 1940, Serial No. 368,434

2 Claims. (Cl. 128—2)

This invention relates to a skin tester method and apparatus, and particularly to allergen applicator method and apparatus.

The primary object of this invention is to provide a method and apparatus whereby a skin tester substance can be applied to the human body by electrophoresis. The object of applying skin testers is usually to determine the skin reactions of patients suffering from allergic conditions with respect to certain substance.

Another object of this invention is to provide a method and apparatus whereby a patient can be simultaneously and speedily tested for reaction to a plurality of different allergenic substances and wherein such substances are carried into the skin by electrophoresis at prearranged spaced areas of the skin.

An object of my invention is to provide a means of selecting and applying at will any one, or a number of allergenic extracts to the skin of the patient.

Another object of my invention is to provide a means of substituting at will, one or a number of said allergenic extracts, and to provide an applicator that will readily receive one or a number of such allergenic extracts individually or plurally so that it can be conveniently applied to the patient.

The conventional method employed at the present time to test the skin of patients is by the commonly called "scratch test," whereby the skin of the patient is broken by a needle-scratch and the introduction of allergenic extracts into the skin.

This so-called "scratch test" method is a very slow and painful operation, requiring in some cases a great length of time to determine the reaction to the various allergens.

My method and apparatus eliminates the necessity of the scratch test, and one or more kinds of allergenic extracts may be introduced into the skin at the same time by electrophoresis, thus a large number of allergenic extracts may be introduced into the skin simultaneously, and under exactly parallel conditions, and the reaction can be speedily observed and determined as to the different extracts.

To accomplish this I provide in a very compact unit, all the electrical instruments, applicators, controls and batteries with which to determine skin reactions in patients, and to fully describe the invention I refer to the drawing, in which—

Fig. 1 is an electrical wiring diagram of my skin tester.

Fig. 2 is a layout showing the panel arrangement and the controls.

Fig. 3 is a section of the instrument through line 2—2 of Fig. 2.

Fig. 4 is a partial top view of the applicator pad.

Fig. 5 is a section of the applicator pad and extract receptacles of the applicator as seen on line 5—5 of Fig. 4.

10 Many persons suffer from allergic conditions due to sensitivity to certain substance. Frequently it is tedious and difficult to determine just which allergenic substance is the cause of the suffering. In my method a test can be speedily performed.

Broadly the steps of the method include the holding of the allergenic substance, such as pollen extract, near the skin, and the carrying of the substance into the skin by electrophoresis. Particularly the steps of the method, as herein illustrated, include the holding of the allergenic substance between an electrode, preferably an anode, and the skin so that the electric current carries particles of the allergenic substance into a pre-selected area of the skin.

In the illustrative embodiment of the invention herein the human body and the allergenic substance are placed in series between a pair of electrodes so that the flow of current carries particles of the substance into a selected area of the body or skin. In further detail the method includes the steps of holding a plurality of different allergenic substances in a predetermined pattern spaced over a selected area of the skin

35 of the body so that each substance acts upon a different point of the skin, and then simultaneously introducing the allergenic substances of the pattern into the skin by electrophoretic action. The allergenic substances, such as pollen

40 extracts, are held in suspension respectively in separate paths of electric current which carry them simultaneously but separately into the skin. The electrophoretic action is accomplished by holding the allergenic substance between an anode

45 and the skin and by holding a cathode to the body on the side substantially opposite to the tested area so that the electricity flows through the body. This testing affords identical comparative tests with a variety of allergens with almost immediately observable result.

50 The location of the observed reaction on the skin automatically indicates the respective allergenic substance by the relative location of the point of reaction in the pattern in which the allergenic substances were arranged and held on the skin,

In my apparatus I make use of a holder pad 6 for holding the testing substances, and a flexible pad or plate 7 to form an electrode, which are adapted to be applied to the body in such manner that the electric current between the pad 6 and the plate 7 is shunted through the patient's body. Electricity is supplied here by a battery 8, the negative terminal of which is connected to the holder pad 6. The positive terminal of the battery 8 is connected to the plate 7.

The holder pad has a plurality of conductor wires 9 imbedded therein connected to the battery 8. Between the negative terminal of the battery 8 and the wires 9 of the pad 6 are connected in series a milliammeter 12, and variable resistors 13 and 14, which control the amount of current flowing through the circuit when the circuit between the pads 6 and the plates 7 is shunted by the patient's body. One of the resistors is capable of fine vernier adjustment. A switch 16 in series with the resistors 13 and 14 is for turning the current on and off. A suitable electric cord 17 extends from the conduits 9 of the holder pad. A plug 18 on the free end of the cord 17 forms a separable electrical connection with suitable jacks 19. Thus when the cord 17 is plugged into the circuit the electric current flows from the negative terminal of the battery 8 through the milliammeter 12, the coarse and the fine resistors 13 and 14, through the switch 16, to the cord 17 and to the conduits 9 in the holder pad 6.

The plate 7 also has a flexible cord 21 thereon adapted to be plugged in suitable jacks 22 which latter are connected to the positive terminal of the battery 8. A fixed or stationary resistor 23 is interconnected between the jacks 22 and the battery 8 so as to limit the amount of current flowing through the circuit to the capacity of the milliammeter 12 should the circuit be accidentally shunted between the plate 7 and the pad 6 by a metal conductor or the like. When the holder pad 6 is applied to one part of the body and the plate 7 is placed on another part of the body an electric circuit is formed through the body of the patient, the current flowing from the holder pad 6 to the plate 7.

The allergenic substances for skin testing are in the path of the current flowing from the holder pad 6 to the plate 7 so as to be carried into the skin by the electric current. For this purpose a holder cup 24 is provided for each allergenic substance. This cup 24 is made of non-conductor material. A holder filling 26, such as cotton, is placed into the cup 24 and contains the allergenic substance to be tested. For instance extracts of pollen or the like allergens are thus held in suspension in the cup 24. In the bottom of the cup 24 is an electrode 27 which extends outwardly from the bottom so as to form a stem of the cup 24. The mouth 28 of the cup 24 opposite the electrode 27 is preferably open so that the filling 26 can be replaced therethrough. The filling 26 protrudes slightly to the outside of the cup 24 so as to cover the outside of the rim of the cup 24.

The electrode 27 of the cup 24 is connected into the electric circuit by inserting it into a socket 29 in the holder pad 6. The socket 29 is suitably connected to the wires or conduits 9 in the pad 6. Inasmuch as the wires 9 are connected to the negative terminal of the battery 8, these electrodes function as anodes. There are a plurality of such sockets 29 provided in

the holder pad 6. These sockets 29 are arranged in the herein illustration in parallel rows so as to accommodate any selected number of electrodes and holder cups for single or multiple testing. The pad 6 is made of flexible, non-conductive material such as sponge rubber. The sockets 29 are made of spaced conductive inserts imbedded in a face of the pad 6. The wires or conduits 9 in the pad 6 are formed into a grid so as to honeycomb over the other face of the pad 6. The sockets 29 are connected in parallel into the electric circuit. Thus when the electrodes 27 are in place the resulting device is a pad with a plurality of separate electrodes spaced from each other in a pattern determined by their relative location in the respective sockets 29 in the pad 6. The bottom of the pad 6 is covered by an insulating flexible cover 31 so as to protect the wires 9. Another perforated cover 32 protects the holder face of the pad 6 so as to leave the openings of the sockets 29 open.

The pad 6 as well as the covers 31 and 32 thereof are flexible and pliable to conform to the contour of the body so that when applied to the patient's body they will allow the allergenic extracts in the holder cups 24 to evenly contact the skin of the patient. In addition a small bag of dry sand, or other suitable flexible weight, can be applied over the pad 6 to further insure even pressure on the pad and on the skin. The face covers 31 and 32 of the pad 6 are preferably made of a material that may be washed after each use thereby to render the pad hygienic.

The entire apparatus can be conveniently accommodated in a case 33 in the manner illustrated in Fig. 3. This case 33 has place for the battery 8. An instrument panel 34 is hingedly secured in place so as cover the bottom compartment of the case. On this panel 34 are mounted the milliammeter 12, the knobs of the variable resistors 13 and 14, the button of the switch 16, and the plug jacks 19 and 22, all suitably connected to the battery 8 in the manner heretofore described. The entire instrument panel 34 can be swung outwardly so as to allow access to the connections and for the replacement of batteries.

The case 33 has a hinged cover 36 which is comparatively deep to allow the storing of the pad 6 and the plate 7 therein. The pad 6 when not in use is placed in this cover 36 so that its flat bottom rests on the bottom of the cover 36. In this position the holder cups 24 face away from the bottom of the cover 36. The plate 7 is then laid over the cups 24 and the cords 17 and 21 are folded over the plate 7. In this manner all the movable parts of the apparatus are flatly folded and conveniently packed within the cover 36 of the case. A flap 37 is hingedly secured in the cover 36 in such position as to cover and protect the plate 7 and the pad 6 in their superposed packed position. This flap 37 is secured in closed or covering position by a suitable friction catch 38 and is handled or pulled by a suitable knob 39. It will be noted that this case houses the instruments, the wires and the power unit and it is exceedingly compact so that it can be transported to the patient's bedside if necessary.

In operation the holder pad 6 and the plate 7 are removed from the cover 36 of the case 33. The desired allergens suspended in separate filters 26 are separately placed into respective holder cups 36 and the filled cups are plugged into se-

lected sockets of the holder pad so as to be arranged in a predetermined pattern. Then the holder pad and the plate are plugged into the circuit as heretofore described. The holder pad 6 is placed and pressed on a selected area of the skin of the patient, for instance on the back of the patient. The pressure is so exerted on the pad that it conforms to the contour of the body and all the allergen holders contact the skin with equal pressure. Then the plate electrode is placed on another suitable part of the body, preferably opposite to the holder pad and is held in contact with the body so that the circuit is shunted through the body of the patient with only a slight gap at the holder cups. Then the switch is turned "on" and the current is permitted to flow through the body from the holder cups to the plate on separate paths issuing from each electrode in the holder pad 6. The allergens are thus separately carried into the skin at points spaced in a pattern predetermined by the selection of sockets in the pad. After the desired period of application the pad is removed from the skin. In the event any of the allergens reacts with the skin it causes the showing of the symptoms of sensitivity. The relative position of the area of the skin affected is then compared with the pattern of the relative location of the testing substances in the pad and the allergen which caused the reaction is thus identified. Then the remedy can be properly prescribed.

While certain features of the present invention are more or less specifically illustrated, I wish it understood that various changes in form and proportion may be resorted to within the scope of the appended claims.

I similarly wish it understood that the mate-

rials and the finish of the various parts employed may be such as the experience and the judgment of the manufacture may dictate or various uses demand.

I claim:

5. 1. In an apparatus of the character described, a holder pad, a plurality of conductors imbedded in the pad so as to be insulated from the pad surface, means extended from the pad to connect said conductor to an electric circuit, a plurality of conductor sockets imbedded in the pad and connected to the respective conductors in the pad, insulator cups open at the mouth to contain allergens carriers, and an electrode stem extended from the bottom of each cup and removably fitting into the respective sockets in the pad so as to hold said cups and allergens in a pattern determined by the locations of the sockets.
10. 2. In an apparatus of the character described, a holder pad, a plurality of conductors imbedded in the pad so as to be insulated from the pad surface, means extended from the pad to connect said conductor to an electric circuit, a plurality of conductor sockets imbedded in the pad and connected to the respective conductors in the pad, insulator cups open at the mouth to contain allergens carriers, and an electrode stem extended from the bottom of each cup and removably fitting into the respective sockets in the pad so as to hold said cups and allergens in a pattern determined by the locations of the sockets, and insulator coverings on the opposite faces of the pad, said pad coverings being flexible
15. 30. 35.

CHARLES O. MORSE.
